UNITED STATES PATENT OFFICE.

SAMUEL E. KALBACH, OF READING, PENNSYLVANIA, ASSIGNOR TO ROEPER CRANE & HOIST WORKS, OF READING, PENNSYLVANIA, A CORPORATION OF PENNSYLVANIA.

FRAME FOR TROLLEY HOISTS.

Application filed November 19, 1924. Serial No. 750,850.

To all whom it may concern:

Be it known that I, SAMUEL E. KALBACH, a citizen of the United States, residing at Reading, in the county of Berks and State 5 of Pennsylvania, have invented certain new and useful Improvements in Frames for Trolley Hoists, of which the following is a specification.

This invention relates to improvements in 10 a combined hoist and trolley device, and the invention consists of a frame, formed in sections, and capable of being mounted upon a trolley to form, substantially, the body thereof, while at the same time the plurality 15 of sections are so arranged as to provide housing and supporting means for the load carrying mechanism and the multiple gear assembly.

The invention consists of forming a hoist 20 and gear frame in sections or units, so that three of said sections will provide the housing and supporting means for both the load carrying mechanism and the gears, the former being provided for by the middle 25 section and one end section, while the latter is provided for by the middle and the other end section, the result being a compact and powerful device in proportion to its dimensions.

The invention is more fully described in 30 the following specification and clearly illustrated in the accompanying drawing, in which:—

Figure 1 is a plan view of the entire 35 trolley and hoist with the parts in position in the frame.

Figure 2 is an end view of the frame, as 40 mounted on the trolley. Figure 3 is a detail view showing the three frame sections, slightly separated, and ready to be bolted together or assembled. Fig. 4 is an end view of one of the end sections of the frame.

The numeral 1 designates the ordinary 45 trolley device for carrying the hoisting mechanism and gears. 2 designates the load carrying mechanism and 3 the multiple gears, all of which are of ordinary or usual construction.

The numerals 5, 6 and 7 designate the 50 three sections of the frame, which, when secured together by means of the bolts 8 and the lugs 9 on the frame sections, will form the complete frame for the device.

The end sections, 5 and 7 are substantially

identical, in that each is formed with the 55 lugs 9 for securing it to the centre section 6, which is formed with registering lugs for engagement with the one end section 5 and with registering depressions 10 to receive the lugs 9 on the other end section, so that, when the three sections are brought together, as clearly illustrated in Figure 3, and bolted together as shown in Figure 1, they will, as assembled, form the body of the trolley; 60 serve as a housing and support for the gearing assembly; and also for a housing and support for the load carrying mechanism.

This frame, made up of three sections, arranged as above described, may be applied 65 to any trolley device of the general character illustrated. It will permit of an ease in handling that would not otherwise be obtainable, and the cost of construction is very 70 materially lowered.

The present structure of frame, permits 75 the elimination of a top suspension of the hoist, inasmuch as it is supported at the sides on the trolley frame, thus gaining head room.

In other words, this structure permits 80 carrying the hoist within the trolley, instead of using the trolley merely as a suspension means for the hoist, thus making it applicable in many instances where an ordinary 85 trolley hoist would not be sufficiently effective.

What I claim is:—

1. A frame for a combined hoist and trolley, comprising two like end sections, each of which is formed with perforated 90 lugs, and a central section having lugs at one side adapted to register with the lugs on one end section and depressions at the opposite side adapted to register with the lugs on the other end section and bolts for 95 securing the three sections together to form a frame.

2. A frame adapted to house and support a load carrying mechanism and a multiple gear for actuating it, comprising three sections, each section having lugs formed thereon and means for securing the three sections together, whereby the load carrying mechanism is supported between one end section and the middle section, and the gearing between the other end section and the middle section. 100

3. The combination of a hoist and a

trolley on which it is mounted, with a frame for supporting the load carrying mechanism and the gearing, said frame being made up of three sections formed with registering lugs and secured together by bolts.

4. A three part frame for a trolley hoist, consisting of two like end sections, each

formed with perforated lugs, and a central section having lugs in register with the lugs on one end section and depressions in register with the other end sections and bolts to secure the three sections together. 10

In testimony whereof I affix my signature

SAMUEL E. KALBACH.
